UNITED STATES PATENT OFFICE.

ALEKSANDER PLUDOWSKI, OF WATERBURY, CONNECTICUT, ASSIGNOR OF ONE-THIRD
TO STANISLAW ORLOWSKI AND ONE-THIRD TO WŁADYSŁAW SZCZEPANIĄK, BOTH
OF WATERBURY, CONNECTICUT.

BATH-BRUSH.

1,211,225.

Specification of Letters Patent. Patented Jan. 2, 1917.

Application filed July 24, 1916. Serial No. 110,922.

To all whom it may concern:

Be it known that I, ALEKSANDER PLUDOWSKI, a subject of the Czar of Russia, residing at Waterbury, in the county of New Haven and State of Connecticut, have invented certain new and useful Improvements in Bath-Brushes, of which the following is a specification.

This invention relates to certain new and useful improvements in bath brushes.

The primary object of the invention is the provision of a bath and toilet article in the nature of a flesh brush possessing flexibility whereby different portions of the body may be operated upon for bathing the same.

A further object of the device is the provision of an elongated flexible brush member designed for bathing purposes and provided with absorbent material whereby the water may pass through the brush during the operation thereof.

A still further object is the provision of a flexible rubber base for a brush adapted for containing an absorbent providing a structure in the nature of a fountain brush.

In the drawing forming a part of this application and in which like designating characters refer to corresponding parts throughout the several views:—Figure 1 is a side elevation of the device. Fig. 2 is a central longitudinal sectional view thereof. Figs. 3 and 4 are transverse sectional views taken respectively upon lines III—III and IV—IV of Fig. 2. Fig. 5 is an enlarged detail sectional view corresponding to an end portion of Fig. 2, and, Fig. 6 is a similar view corresponding to a side portion of Fig. 2.

The present device being applicable for bathing purposes consists of an elongated casing 10 formed of a flexible material such as rubber arranged with annular rows of perforations 11 extending therethrough and communicating with the interior of the casing which latter is adapted to contain an absorbent material 12. The absorbent material 12 is preferably in the form of pieces of sponges adapted to receive and absorb water entering within the casing 10 through the perforations 11 thereof.

The casing 10 is provided with opposite pointed end portions 13 conical in form while brush forming bristles 14 are carried

in annular arrangement upon the said casing, being secured by vulcanization or otherwise to annular ribs 15 positioned between the rows of perforations 11. Operating handles 16 extend longitudinally within the casing ends 13 being provided with stop collars 17 designed as packing members at the pointed ends 18 of the casing while finger receiving loops 19 are provided at the outer ends of the said rods. Rings 20 are secured within annular projections 21 within the casing 10 positioned substantially at the base of the end portions 13 thereof, the inner ends of the rods 16 being secured to the rings 20 by means of radially arranged braces 22 carried by the said rings 20.

Upon positioning the device in water, the absorbent 12 will be filled therewith, expanding and filling the casing 10. The rods 16 and loops 19 may be grasped by the bather and upon pressing the bristles 14 against the body, the water will pass outwardly from the absorbent 12 through the perforations 11 adjacent the brush portion of the device, the entire structure being flexible and readily employed for the purposes for which it is designed.

What I claim as new is:—

1. A brush comprising an elongated flexible casing tapered at its opposite ends and provided with annular rows of perforations, absorbent material arranged within the said casing, and bristles annularly arranged upon the casing intermediate the said rows of perforations.

2. A brush comprising an elongated flexible casing tapered at its opposite ends and provided with annular rows of perforations, absorbent material arranged within the said casing, bristles annularly arranged upon the casing intermediate the said rows of perforations, rings secured within the casing adjacent the ends thereof, radial braces carried by the said rings, and operating rods having their inner ends secured to the said braces positioned axially of the casing and projecting outwardly through the opposite pointed ends of the latter.

3. A body brush comprising an elongated casing having conical end portions, the said casing being formed of flexible material provided with a receiving chamber therein and having annular rows of perforations communicating with the said chamber, an ab-

sorbent filling for the said casing arranged within the said chamber, annular ribs upon the casing intermediate the said rows of perforations, and annular rows of bristles carried by the said ribs.

4. A body brush comprising an elongated casing having conical end portions, the said casing being formed of flexible material provided with a receiving chamber therein and having annular rows of perforations communicating with the said chamber, an absorbent filling for the said casing arranged within the said chamber, annular ribs upon the casing intermediate the said rows of perforations, annular rows of bristles carried by the said ribs, annular pro-

jections arranged within the casing positioned substantially at the bases of the said end portions, rings secured within the said projections, operating rods arranged axially of the casing having their inner ends centrally secured within the said rings, the said rods projecting in opposite directions through the pointed ends of the casing, packing washers upon the said rods in spaced relations inwardly and outwardly of the said pointed ends, and finger loops upon the outer ends of the said rods.

In testimony whereof I affix my signature.

ALEKSANDER PLUDOWSKI.
